UNITED STATES PATENT OFFICE.

JESSE DITSON, OF LITTLETON, COLORADO, ASSIGNOR TO THE J. GEO. LEYNER ENGINEERING WORKS COMPANY, OF LITTLETON, COLORADO, A CORPORATION OF COLORADO.

DRILL-SHARPENER.

1,304,459.

Specification of Letters Patent. Patented May 20, 1919.

Application filed February 16, 1917. Serial No. 149,033.

To all whom it may concern:

Be it known that I, JESSE DITSON, a citizen of the United States, residing at Littleton, in the county of Arapahoe and State 5 of Colorado, have invented a certain new and useful Improvement in Drill-Sharpener, of which the following is a specification.

This invention relates to drill sharpeners and more in particular to a device for pinning out the drill steel before or after having been sharpened.

The object of my invention is to provide an improved means conveniently located and mounted on the drill sharpener for pinning 15 out steel to be sharpened or a newly sharpened drill steel; also, to provide means for operating the pinning out means by fluid pressure; to provide a vise to be used in conjunction with the pinning out means 20 which is mounted on the drill sharpener, and further, to provide means to adjust the vise to be used in pinning out drill steels of various diameters.

As is well known in this art a hollow 25 drill steel when sharpened, especially by machine, is apt to have its central bore more or less clogged or obstructed during the sharpening operation. This is due to the crowding of the metal forming the cutting 30 edges into the central bore by the repeated blows of the sharpening dolly or shaping tool. In order, therefore, that the central bore of the drill may be enlarged or freed 35 from obstructions of this kind it is usual to force a pin substantially of the diameter of the bore into the drill steel.

In order to accomplish this conveniently 40 and expeditiously the pinning out means are preferably mounted upon the same base as the sharpening means.

In the drawings annexed hereto and forming a part of this application,

Figure 1 is a side elevation of my improved sharpener,

Fig. 2, a plan view of the same,

Fig. 3 an end elevation of the same,

Fig. 4, a cross sectional view of the valve operating the pinning out piston.

Fig. 5, a cross sectional view of the vise 50 used in connection with the pinning out means,

Fig. 6, the adjustable lower jaw of the vise,

Fig. 7, the adjustable wedge for this jaw,

Fig. 8, the handle and pinion for operating the adjustable wedge, and

Fig. 9, the index plate shown in position.

In the construction disclosed in the drawings, 1 is a portion of the base of my sharpener having upper and lower jaw members 60 2 and 3, respectively, between which the drill is adapted to be securely clamped during the sharpening process. Preferably the upper jaw member 2 is operated by fluid pressure such as compressed air acting 65 through a rod 5 upon a piston in a cylinder, (not shown). The drill while being securely held in position and while heated is struck repeatedly by the forming dolly 6, by which it is shaped and sharpened. During this operation the drill operated upon, if of a hollow type, is obstructed by the flow of metal into the central bore from the parts being shaped and sharpened. It therefore becomes necessary to provide some way in 70 which the central bore may be cleared of these obstructions. In order to accomplish this conveniently and expeditiously, a cylinder 7 is mounted upon the base of the sharpener at one side of the clamping jaws 80 2 and 3. In this cylinder a piston 8 is forced forwardly and rearwardly by means of fluid pressure which may be furnished from the same source as that by which the clamping 75 jaws and forming dolly are operated. Extending forwardly from piston 8 is a rod 85 or pin 9 which passes out of the cylinder through a stuffing box 10. In order to conveniently insert and remove the pin 9 a sleeve 11 is fastened to the piston and extends rearwardly from the cylinder and passes out of the same through a stuffing 90 box 12 which is fastened to the rear face of the cylinder by means of a plate 13 and bolts 14. Through a central hole 15 in the sleeve 95 11 a distance piece 16 extends which rests against the rear end of pin 9 and is held in place in the sleeve by the cap 17 fitting over the rear end of said sleeve 11. The movements of the piston 8 may be conveniently controlled by a valve 18 located beneath the cylinder 7, as clearly shown in Fig. 4, operated by a handle 19 connected to the valve by rod 20.

To hold the drill steel while being pinned 105 out a vise is provided, the upper and lower jaws of which are formed by extensions 21 and 22 of the clamping jaws 2 and 3 respec-

tively. To prevent undue wear and to hold the drill properly in line a hardened V-shaped plate 23 is secured by screws 24 in the upper jaw 21. The lower jaw of this 5 pinning out vise is made adjustable in order that steels of different diameters may be set in the vise at the proper position to bring the central hole in alignment with the pin 9. To accomplish this a bottom clamping block 10 25 is set into the lower jaw 22, the lower edge of which is beveled as shown at 26 under which a wedge 27 is adapted to slide. From the construction it is obvious that 15 by moving the wedge to the right or left as shown in Fig. 5 the lower clamping block is adapted to be raised or lowered. Preferably the wedge 27 is provided on its lower side with a rack 28 adapted to mesh with a section of a pinion 29 to which is fastened a 20 handle 30. To securely lock the pinion 29 and consequently the wedge 27 in position the handle 30 is provided with a spring pressed stud 31 extending inwardly from said handle 30 and engaging any one of a 25 series of holes 32 formed in an index plate 33 mounted upon the lower jaw member 22. If desired, suitable indications may be placed near each of the holes 32 in order to conveniently indicate for what size drill the 30 clamping block 25 is set.

It will thus be seen from the above description that I have provided a device in which a drill steel, or a drill bit, after it has been sharpened in the usual manner, 35 may readily be pinned out by pressure exerted by the same fluid as that used for sharpening the drill steel. While the operation of my device may be obvious from the above description, a brief outline of the method of 40 using the device will be given.

The drill steel is placed on the lower block 25 after this block has been adjusted to the proper position to accommodate the diameter of the steel being operated upon. 45 The upper movable jaw 21 is then lowered in the same manner as when using this jaw member in sharpening the steel. With the steel securely fastened in place the handle 19 is operated to move the valve 18 to admit 50 fluid pressure to the rear of the cylinder 7, thrusting the piston 8 forwardly and advancing the pin 9 toward the jaws of the vise 23 and 25. This advance movement of the pin 9 is accomplished with such force that

the pin 9 is thrust well into the drill steel 55 and completely clears the central bore of any obstruction. The piston may then be reversed by throwing the valve 18 in the opposite direction by means of the handle 19. If desired this operation may be repeated a 60 number of times, or until the central bore of the steel is completely cleared of obstructions.

It is to be understood that while the present showing and description discloses only 65 one specific modification of the present invention, other forms and embodiments are included within the spirit and scope thereof, as expressed in the appended claims.

What I claim is:

1. In a pinning out device for drill steels mounted upon a drill sharpener base, a piston adapted to reciprocate within a cylinder, said piston carrying a pin, and a fluid operated pinning out vise mounted upon said 75 sharpener base, said pinning out vise having a movable jaw member, a stationary jaw member and an adjustable jaw member inserted within said stationary jaw member and adapted to coöperate with said pin 80 whereby drill steels of different diameter may be held in alignment with said pin.

2. In a vise for holding a drill steel in position relative to a reciprocatory pin, a movable member and a stationary member, said 85 stationary member having an adjustable member inserted therein, a wedge member, movement of which varies the position of said adjustable member, and means to hold said wedge member in any desired position 90 whereby drill steels of different diameter may be held in alignment with said pin.

3. In a vise for holding a drill steel in position relative to a reciprocatory pin, a movable member and a stationary member, said 95 stationary member having an adjustable member inserted therein, a wedge member movement of which varies the position of said adjustable member, said wedge member having gear teeth meshing with gear teeth 100 provided on a pinion, rotation of said pinion serving to alter the position of said wedge and adjustable member whereby drill steels of different diameter may be held in alignment with said pin.

In testimony whereof I have hereunto set my hand.

JESSE DITSON.
